WILLIAM B. McCRAY, OF WINCHESTER, INDIANA

CHICKEN FEEDER

Application filed May 18, 1931. Serial No. 538,299.

This invention relates to chicken feeders and has for its object the provision of a simple, strong, durable, inexpensive device by the use of which poultry may obtain an adequate supply of feed without crowding or wasting the feed.

A further object of the invention is to provide a structure for the stated purpose, of such form that the fowls cannot roost thereon and which will facilitate cleaning of the same so that it may be easily kept in a sanitary condition.

Other objects of the invention will appear incidentally to the course of the following description.

In the accompanying drawing:—

Figure 1 is a side elevational view of the chicken feeder.

Figure 2 is a transverse sectional view thereof.

The chicken feeder comprises upright legs 1 which are connected together in pairs by cross pieces 2. Perch planks 3 extend longitudinally of the device and are connected 25 with the legs 1 at points below the upper ends thereof. The legs 1, cross pieces 2 and perch planks 3 form a frame which supports the feed receptacle of the device.

The feed receptacle consists of end pieces 30 4 which are attached to the cross pieces 2, a bottom wall 5 which extends longitudinally of the device and connected at its ends with the end walls 4. The bottom wall 5 is located above the perch plank 3 and is spaced 35 above the level of the said plank. The bottom wall 5 is divided into trough compartments 6 which are separated from each other by an upstanding portion 7 which lies upon the median longitudinal dimension of the bottom wall 5. Inclined boards 8 are attached to the end walls 4 and the lower edges 40 of the boards 8 enter the troughs 6 but are spaced above the upper surfaces of the said troughs. Spaced rods 9 extend upwardly 45 from the outer edges of the bottom wall 5 and are connected at their upper end with the upper portion of the board 8. A roof plank 10 is mounted in an inclined position upon the upper edges of the end walls 4 and the lower portion of the roof plank 10 ex-

tends beyond the outer surface of one of the boards 8. A roof plank 11 is hingedly connected with the upper edge of the roof plank 10 and is adapted to lie upon the upper edges of the end walls 4 and the free end portion of the plank 11 is adapted to extend beyond the upper edge of one of the inclined boards 8. Upstanding pins 12 are mounted upon the roof plank 11 and serves to prevent fowls from roosting upon the feeding device.

The feed is deposited in the feed receptacle and gravitates down along the inner surfaces of the inclined boards 8 and flows into the troughs 6. The fowls may hop upon the perch plank 3 and by passing their heads through the spaces between the rods 9 they partake of the feed in the troughs 6.

Having described the invention what is claimed is:—

A poultry feeder comprising a receptacle having a top, a bottom wall divided into compartments, spaced rods rising from the outer edges of the bottom wall of the receptacle, inclined side boards located within the receptacle and having upper edges meeting the upper ends of said rods and a roof board hinged to the top of the receptacle and when closed having an edge portion resting upon the upper ends of one row of rods and extending beyond the vertical plane of said row of rods and the outer edge of one of the bottom compartments.

In testimony whereof I affix my signature.

WILLIAM B. McCRAY.
